UNITED STATES PATENT OFFICE.

THOMAS W. MELLOR, OF PHILADELPHIA, PENNSYLVANIA, ASSIGNOR TO
JAMES AND FREDERICK R. GILLINDER, OF SAME PLACE.

DESIGN FOR GLASS TUMBLERS, &c.

Specification forming part of Design No. **7,186**, dated February 17, 1874; application filed November 28, 1873.
[Term of Patent 7 years.]

To all whom it may concern:

Be it known that I, THOMAS W. MELLOR, of the city of Philadelphia, in the State of Pennsylvania, have Invented an Ornamental Design for Glassware, of which the following is a specification:

The nature of my design is fully represented in the accompanying drawing, to which reference is made.

A B represent a glass tumbler having my said ornamental design cut or cast in or upon the outer side of the same, the said design consisting of a surrounding series of sharp-bottomed sloping depressions, *c c*, and sharp-edged sloping projections *d d*, surrounding a slightly-raised rectangular flat center, *f*; the

whole together forming the ornamental design around the outer side of the glass vessel to which it may be applied, as shown in the drawing. My said design is not intended to be for glass tumblers only, but for goblets, decanters, pitchers, and all other articles of glassware to which it may be applied.

I claim as my invention—

A design for glassware, consisting of the series of sharp-bottomed sloping depressions *c c*, and sharp-edged sloping projections *d d*, surrounding a slightly-raised rectangular flat center *f*, as shown and described.
